UNITED STATES PATENT OFFICE.

FREDERICK C. KING, OF SYRACUSE, NEW YORK, ASSIGNOR TO KING SHIPPING CASE CORPORATION, OF SYRACUSE, NEW YORK, A CORPORATION OF NEW YORK.

COLLAPSIBLE CASE.

1,322,700.

Specification of Letters Patent. Patented Nov. 25, 1919.

Application filed November 2, 1916. Serial No. 129,099.

To all whom it may concern:

Be it known that I, FREDERICK C. KING, a citizen of the United States, and a resident of Syracuse, in the county of Onondaga and State of New York, have invented a certain new and useful Collapsible Case, of which the following is a specification.

This invention has for its object a collapsible case particularly adapted for shipping furniture or other goods which must be cleanly and carefully packed; which case is particularly simple in construction and highly efficient and durable in use; and the invention consists in the combinations and constructions hereinafter set forth and claimed.

In describing this invention, reference is had to the accompanying drawings in which like characters designate corresponding parts in all the views.

Figure 1 is a side elevation of a preferable embodiment of this collapsible case.

Fig. 2 is an end elevation, the bottom being shown as folded upwardly preliminary to the collapsing of the case and the door being removed.

Fig. 3 is a top plan of the case.

Fig. 4 is a horizontal sectional view thereof, the position of the door preliminary to the collapsing of the case being indicated in dotted lines.

Fig. 5 is a diagrammatic view illustrating the collapsing action of the case.

Figs. 6 and 7 are fragmentary views illustrating respectively, the latch for the door, and contiguous parts, and one of the joints between one end and the side walls of the body.

This collapsible case comprises, generally, a rectangular body collapsible from its rectangular form into a flattened rhomboid form, walls of said body being foldable preliminary to the collapsing action, into positions contiguous to other walls which form the sides of the rhomboid. The case also comprises truck wheels carried at the lower edges of the upright sides of the body.

The body is composed of upright sides, 1, 2 opposite end frames or walls 3, 4, a bottom wall 5, and a top wall 6.

These walls are composed of angle iron frames which support a sheet metal casing, with the exception of the wall 4 which is

composed of a frame only and the bottom 5 which is a wood floor.

In this form of my invention, the body is collapsible horizontally from its rectangular form into a rhomboid form and the frames of the sides and ends are pivoted together as at 7 on vertical pivots, the pivots extending through lapping portions of the angle iron frame elements 8 of the side and end walls. The bottom 5 is hinged on one edge at 10 to the lower horizontal frame bar of the side 2, and rests at its other or free edge 65 on the lower horizontal frame bar of the side 1, the floor fitting within the rectangle inclosed by the lower margins of the side and end walls and holding the body from collapsing. The floor swings inwardly and upwardly against the inner side of the wall 2 preliminary to the collapsing of the case.

The open end wall 4 of the case is closed by a suitable door 12.

Reinforcing bars 13 of angle iron are also disposed centrally midway between the ends of the case, these bars 13 being pivoted at 14 to the upper and lower frame bars of the side walls 1, 2.

The door 12 at one end of the case is hinged at 15 to an upright angle iron frame bar of the side 2 and laps at its free end the upright angle iron frame bar of the side 1. Said door 12 is held in its closed position by suitable latches 16 pivoted at 17 to the door 12 and having hooks or bills 18, Fig. 6, movable through openings in the studs 19 projecting through the flange of the upright angle iron bar at the contiguous edge of the side wall 1.

When the case is closed ready for shipment, the latches 16 may be sealed or locked in their closed position.

The top wall 6 is also preferably movable in order to permit the collapsing and setting up of the case and this top wall is here shown as hinged at 20 to the upper horizontal angle iron of the side 1 and is foldable outwardly from its position shown in Fig. 2, into a position in which it hangs contiguous to the outer side of the wall 1. The top wall also fits within the rectangle formed by the upper margins of the side and end walls and holds the case from collapsing.

When the floor is folded into the position

shown in Fig. 3, and the top into the position shown in dotted lines, Fig. 2, and the door 12 folded into the position shown in dotted lines, Fig. 4, the case can be collapsed.

5 The top wall is provided with locking means as pins 21 which extend through openings 22 in the end angle iron frame bars of the top wall 6, and into the aligned openings in the upper horizontal frame pieces of the ends 3, 4. The pins are locked from the inside of the case by keys passed through transverse openings 23.

10 Suitable wheels as truck wheels 24 and 15 caster wheels 25 are provided at the lower edges of the upright sides 1, 2, these wheels being supported in bearings carried by the lower horizontal angle irons of the sides 1, 2.

15 The vertical angle iron pieces 26 of the 20 end 3 are located to the inside of the contiguous flanges of the vertical corner pieces 27 of the side walls 1 and 2 in order to permit collapsing of the case as indicated in Fig. 7.

25 This case is particularly efficient in that it provides a strong, durable, dry and dust-proof compartment for furniture or any articles which are to be carefully handled during shipment, and in that it can be 30 readily collapsed and handled for reshipment when empty. It is further advantageous in that it is held from collapsing by the bottom and the top walls, and is readily locked when set up by two pins coaxing with the top wall.

35 Obviously, a collapsible case for the purpose described would be a difficult object to move even when collapsed, but by providing the upright sides 1 and 2 with the truck wheels 24 and the caster wheels 25, this collapsible case can be easily moved, either in its open or collapsing position as the wheels 24 and 25 are always in their operative positions.

40 45 What I claim is:—

1. A collapsible case comprising a rectangular body including a top, bottom, side and end walls, the body being collapsible horizontally from a rectangular form to a 50 flattened rhomboid form, and the bottom wall being foldable upwardly, and the top wall being foldable preliminary to the collapsing of the body, and means for locking the top in its closed position from the inside 55 of the body, the body having a door at one end, substantially as and for the purpose described.

holding the bottom wall from downward movement and means on the inside of the body for locking the top in its closed position and truck wheels provided on the body 5 at the lower edges of two of the upright side walls, substantially as and for the purpose set forth.

6. A collapsible case comprising a rectangular body including bottom, top, side and 10 end walls, the body being collapsible from a rectangular form into a flattened form and the side walls being moved inwardly and outwardly to and from each other in the folding and unfolding of the case, and 15 wheel trucks provided on the body at the lower edges of the opposite side walls and carried by the latter in their inward and outward movements.

7. A collapsible case comprising a rectangular body including bottom, top, side 20 and end walls, the body being collapsible from the rectangular form into a flattened form, and the side walls being movable toward and from each other in parallelism in the folding and unfolding of the case, and 25 truck wheels provided on the side edges of the parallel walls and carried by the same in their inward and outward movements to and from a position in transverse alinement and arranged for use when the 30 case is either collapsed or unfolded.

In testimony whereof, I have hereunto signed my name, at Syracuse, in the county of Onondaga, and State of New York, this 19th day of October, 1916.

FREDERICK C. KING.
